ADOLPHE C. PETERSON, OF MINNEAPOLIS, MINNESOTA

SUPERCHARGING DUAL CYCLE ENGINE

Application filed July 9, 1927. Serial No. 204,644.

My invention relates to internal combustion engines and particularly to a form of engine which has supercharging and dual cycling characteristics wherefore it is called 5 a supercharging dual cycle engine.

The principal objects of my invention are to provide an engine which shall have simplicity, efficiency, flexibility and durability, and which shall be cheap comparatively in manufacture and which shall be simple in maintenance. An object of my invention is to provide an internal combustion engine which shall be easily started, which shall be easily given a preheat for easy starting and 10 for starting under conditions of utmost efficiency. An object of my invention is to provide an engine starting system in conjunction with internal combustion engines which starting system shall be simple and shall require less draught on the electrical current of a starting battery. An object of my invention is to provide a form of valve operating means which is simple in operation, simple 15 in construction and simple in maintenance and which shall be automatically adjustable or which shall require no adjustment of the valve operating means such as is usually required in connection with poppet valve engines. An object of my invention is to provide an engine which shall be capable of operating upon either the four cycle plan of 20 operation or the two cycle plan at the will of the operator or driver and to provide in connection therewith a simple means for effecting the changing in the valve operation to effect the two cycle or four cycling changing. In general the object of my invention is to 25 provide an improved internal combustion engine.

The principal devices and combinations of devices comprising my invention are as hereinafter described and as defined in the claims. In the accompanying drawings which illustrate 30 my invention like characters refer to like parts throughout the several views.

Referring to the drawings:

Figure 1 is a view chiefly in vertical section in a plane passing through the axial center 35 of the crank shaft of an engine embodying

my invention. Some parts are shown in full side elevation and some parts cut away.

Figure 2 is a section on the line II—II of Figure 1 on a vertical plane at right angles to that of figure.

Figure 3 is a section on a horizontal plane taken on the line III—III of Figures 1 and 2, this section showing particularly the pre-heating means.

Figure 4 is a section on the line IV—IV of Figures 1 and 2 this section being on a horizontal plane passing through the inlet and exhaust manifolds of my engine.

Figure 5 is a section through a part of the control valve governing the starting function, on line A of Figure 1.

Figure 6 is a section through a part of the control valve governing the two cycling function, on line B of Figure 1.

Figure 7 is a section through a part of the control valve governing four cycling function on line C of Figure 1, and particularly governing the exhaust valve in such cycling.

Figure 8 is a section through a part of the control valve governing four cycling function on line D of Figure 1 and particularly governing the inlet valve in such cycling. Sections on the lines E and F of Figure 1 through the ports of the control valve governing the exhaust and inlet valves respectively of the other cylinder 2 are substantially similar to the ports as shown in Figures 7 and 8 but they are so placed as to procure the proper cyclic action as hereinafter described.

Figure 9 is a section on the line XI—XI of Figure 1, on a vertical plane at right angles to that of Figure 1.

Referring again to the drawings, the numeral 1 indicates a crank case which may be constructed or cast integrally with cylinders 2 and has secured to its under side the lower part 3 of the crank case. A crank shaft 4 is rotatably mounted in the crank case portions and by its cranks cooperates with crank rods 5 which individually are actuated by pistons 6 one reciprocably placed in each cylinder 2.

The cylinders 2 each have one inlet valve of the poppet type, 7, and one exhaust valve, poppet type, 8, which respectively are nor-

mally raised by coil springs 9, against their seats in the cylinder heads 10. The upper ends of the valve stems 11 each have a small piston called a valve piston 12 fixed to or constructed integrally with the valve stem. The valve piston 12 of each valve is reciprocable vertically in a so-called guide cylinder 13, the fit being such that there is little or no leakage around the piston but so that the 10 valve piston has an easily slid able fit in its cylinder. So-called waste ports 14 in the lower sides of the guide cylinders beneath the location of the valve pistons permit discharge of any oil which may leak downward 15 from above the valve pistons, into spaces or chambers 15.

A control valve casing of a substantially cylindrical form is cast integrally with the heads of the cylinders or is separately constructed and attached thereto and has bearings 16, 17 at its ends, the control valve casing being denoted 18. In the bearings 16, 17 a control valve 19 is rotatably mounted by its one end 20 of a cylindrical form and by 25 its other end 21 which has a short cylindrical portion and also a square portion 22 which latter is slid able axially in a mitre gear 23, the latter being rotatably mounted as shown in a bearing 24. The square portion 22 30 passes through a square hole in the mitre gear 23 so that the latter drives the control valve 19 uniformly with it thereby.

The control valve 19 is cylindrical and its interior is hollow and forms a conduit 25 thereby. The control valve 19 has control portions which are shown in sections in the Figures 5, 6, 7, 8, and these control portions are so formed that in the parts which extend to the inner surface or wall of the control valve 40 casing 18 and slide closely against it they have ports 26, 27, 28, 29, respectively, which are adapted, depending on which is placed in cooperation with a port 30 in the guide cylinder related to it, to permit the entry 45 of oil or liquid under pressure from the conduit 25 to the interior of the guide cylinder above the valve piston. It is to be noted that the Figures 5, 6, 7, 8, show the control portions or sections related to one guide cylinder 50 only, each cylinder 2 with its guide cylinders having similar sets of sections in the control valve 19, for its valves. The control valve 10 is slid able axially as controlled by a hand wheel 31, the latter mounted by a ball bearing 55 on the end of the shaft 20 of the control valve 19. Thereby the control valve may be placed so that either the section A related to each guide cylinder is in cooperation with its related port 30 or that the section B related 60 to each guide cylinder is in cooperation with its related port 30 or so that the sections C and D are in cooperation with the ports 30 of one exhaust valve and one inlet valve of each cylinder 2 respectively.

35 The control valve 19 in portions removed

from the control sections is somewhat recessed from the inner wall of the casing so that these recessed portions will permit any oil or liquid to flow from these recessed portions to the ports 32 in the casing and thence to spaces 15, thereby there is provided means whereby substantially whenever any guide cylinder 13 is not receiving oil or liquid under pressure from conduit 25 it may discharge liquid to spaces 15 and thence as hereinafter described to the reservoir. Thus the guide cylinders are freed from pressure at proper times and the valve springs related to the poppet valves will accordingly seat their valves. The recessed portions as they are at the control sections are denoted 33.

The control valve 19 by its conduit 25 receives oil or liquid under pressure from an annular chamber 34 through ports 35 constantly in its rotation. The annular chamber 34 receives oil or liquid under pressure through conduit 36 from ports controlled by ball check valves 37 in a pump housing 38. The pump housing 38 has two chambers of a cylindrical form wherein respectively two eccentric pump pistons 39, 40 revolve the eccentric pistons being secured to the crank shaft 4 to revolve with the latter. The eccentric pistons 39, 40 draw oil or liquid from a reservoir or crank case by supply conduit 41 ball check valves 42 preventing return flow. Slide blocks 43, 44 slid able in closely fitted slide chambers or recesses in the housing 38 are adapted to continuously press against the respective eccentric pistons in rotation of the latter, coil springs 45, 46 pressing the slide blocks thereagainst. The spaces 15 may return liquid to the reservoir by means of a return conduit 47.

In the immediate neighborhood of the engine or fixed upon a bracket or other support, an electric motor is adapted to drive two centrifugal impellers 48, 49 respectively, one being fixed to revolve with each end of the shaft 50 of the motor (electric) 51. The latter is driven by a storage battery 52. It is contemplated that the storage battery will be charged continuously by a generator driven by the crank shaft 4.

One of the centrifugal impellers may deliver to either a conduit 53 or conduit 54 as governed by a valve 55 manually controlled. The conduit 53 delivers to a combustion chamber 56 a backfire preventing screen 57 being interposed. The combustion chamber 56 is relatively large and delivers at its two ends to chambers 58, 59 which deliver to tubes 60, 61 the latter welded in the cast body of the water jacket 62 so that they lie parallel to the cylinders at their sides in the lower portion of the water spaces 63 on each side of the cylinders 2. The tubes 60, 61 at their other ends deliver to the atmosphere either directly or indirectly by any conduit.

30 The conduit 54 delivers to a chamber 64 in

the cylinder head and chamber 64 delivers permanently into inlet manifold 65 and may as controlled manually by a hand valve 66 deliver through ports 67, 68 to the exhaust manifold 69, the latter under such conditions being shut off from the exhaust conduit 70. Under conditions when the exhaust manifold 69 is cut off from the chamber 64 and thereby from conduit 54 the exhaust manifold will be open to the exhaust conduit 70, the latter delivering to the atmosphere.

The other centrifugal impeller delivers either to the conduit 54 or to a conduit 71 as controlled by a hand valve 72. The conduit 71 delivers (when connected by hand valve 72) to inlet ports 73 one located in the side of each cylinder 2 at such height that the related piston uncovers it at its lowermost point of reciprocation, substantially as in other engines of the two cycle type. Opposite to the inlet ports 73 are exhaust ports 74 delivering to the atmosphere. The exhaust ports 74 deliver through a conduit 75 to atmosphere and the conduit 75 may or may not be blocked 25 by a hand valve under certain conditions of operation if desired.

One of the impellers always draws carburetted air from the Venturi tube 76 and this impeller is the one which may deliver either to conduit 53 or 54. The Venturi tube 76 has a normal nozzle which delivers under suction a flow of fuel liquid sufficient to give to the air passing through a normal ratio of fuel sufficient to form as nearly efficient combustible proportion as may be. A supplementary nozzle 77 controlled by a hand valve 78 may be permitted to deliver or not as the operator desired by opening or closing valve 78, the supplementary nozzle being so proportioned however that it will deliver if in action a quantity of fuel sufficient to form with the fuel issuing from the normal nozzle a rich or supernormal carburetted air flow from Venturi tube 76. The Venturi tube may be connected with the other impeller by means of hand valve 79 or that other impeller may be connected with atmosphere by that hand valve 79.

The control valve shaft and mitre gear 23 are driven by mitre gear 80 and the latter by vertical shaft 81 by mitre gears 82, 83 and thereby by crank shaft 4 the relation being such that the control valve is driven at half the speed of the crank shaft 4. The valve sections B related to two cycle action are of such form that communication is permitted twice in each revolution of control valve 19 and the sections C, D, are each adapted to permit communication only once in each revolution of control valve 19.

The conduit 36 has related to it a hand pump 84 which may be manually operated to draw oil and force it under pressure to the conduit 25.

Spark plugs 85 have such related electric

current creating and governing means (not shown) that electric sparks may pass at proper times for either two cycle or four cycle action a distributor 86 providing for two cycle action and a distributor 87 for four cycle action. A spark plug 88 may be caused to emit sparks as desired in the combustion chamber. In the operation of my engine, the engine being cold, the operator sets the hand valves so that carburetted air (normally carburetted) will pass from one impeller to the combustion chamber 56 and so that the spark plug 88 causes combustion therein. The operator may set the hand valves so that the other impeller also draws carburetted air and delivers it to the chamber 64 and may thence deliver to the cylinders 2 and be combusted by action of the spark plugs therein. But the hand valves are preferably so set that the other impeller does not draw either air or carburetted air under this preheating condition. The combustion products from combustion chamber 56 will pass through the tubes in the water spaces and thereby heat the water therein which will circulate and

heat the cylinders 2 and prepare them for efficient starting action under such conditions that there will be but little or no crank case dilution. When so preheated, the operator may set the hand valves so that normally carburetted air will flow to both of the impellers and thence to chamber 64 and may set the control valve so that sections A cooperate with all ports 30, and these sections are such that there will then be communication between conduit 25 and guide cylinders and so that by actuating hand pump 84 oil may be forced manually into all the guide cylinders and thereby depress all the inlet and exhaust valves and so that thereby the impeller will draw carburetted air and pass into the cylinders 2, all of them (under this action the hand valve 66 is set so that exhaust manifold may deliver to the exhaust conduit but may be set the other way). A charge of combustible gas is thereby passed into each cylinder 2 and the operator may then cause distributor 87 to cause a spark to be emitted in proper cylinder according to the cyclic action and thereby rotation is caused of crank shaft 4. The distributor 87 should be manually alterable, that is advanceable or retardable so that the operator may slightly shift the distribution to cause more certain ignition or of course the distributor and sparking means may be such that there will be sparks at any time of the working stroke. In description, the action is described as if there are the usual plurality of cylinders six or eight or otherwise, only two being shown. These two in

four cycle action have alternate working strokes and in two cycle action fire together. It is contemplated that there will be four, six or eight preferably of such sets of two cylinders.

When the engine is thus given initial rotation it takes up its cycle of operation. In the starting action that is when being given the initial revolution, after the preheating, the control valve is so set manually that the four cycle sections, that is, the sections C and D cooperate with the inlet and exhaust valve guide cylinders, (the hand pump is then inactive) and the result will be as soon as the control valve is shifted to this starting position or cranking position, the oil will be released from the guide cylinders related to cylinders 2 in which the pistons are in some part of the working stroke, and consequently the poppet valves related to that cylinder or cylinders will be permitted to close and this cylinder or cylinders will be in condition for effective working effort when a spark is caused in its spark plug. This the operator causes by causing the distributor effective for four cycle operation to be effective and by manipulating it for advancement or retardation of the spark as necessary until a spark is caused and causes revolution of the crank shaft 4. When so started the engine is in condition for effective continuation of the revolution as the passages have been filled up with the combustible carburetted charge, and the slightest revolution of the crank shaft will cause further effective combustion and working strokes in the cylinders 2.

In the normal operation of a four cycle engine, the eccentric pistons cause a pumping of liquid oil or other easily flowing liquid from the eccentric pistons or pump housing to the conduit 25 and as the control valve revolves half as fast as the crank shaft 4 the sections C and D, then in cooperation, (control valve being so placed) the sections C and D related to each inlet and exhaust valve will permit the oil to enter under pressure to the related guide cylinder at the appropriate time for depression or opening of the poppet valve related and thereby the valve piston will be forced by the oil pressure downward and thereby open the poppet valve, the inlet valve of each cylinder being opened during substantially the entire suction stroke, the exhaust valve being opened during substantially the entire exhaust stroke and the two valves being both closed during substantially the entire two succeeding strokes, that is the usual compression and working strokes, combustion occurring during the working stroke. The timing may be altered as necessary to secure most efficient flow of gases and expansion in the working stroke. The engine will thus carry on its cycle as a four cycle engine.

If now it is desired to operate the engine on the two cycle as when an especially heavy load is encountered as when hill climbing or at relatively slow speeds in heavy roads, or if maximum power is required, the operator

then shifts the control valve so that the B sections are in place for cooperation with the ports 30 and in this case the engine being then under way and the hand valve 66 being shifted so that the exhaust conduit is closed from the exhaust manifold and the chamber 64 is open to the exhaust manifold, the impellers will then deliver as follows: (the valves being accordingly set) the impeller drawing carburetted air from the Venturi tube will deliver to chamber 64 and thence to the inlet and exhaust manifolds and thence as the valves are opened to the cylinders 2, and the other impeller will deliver pure air from the atmosphere to the ports in the side of the cylinders 2, the air passing into the cylinder 2 when the port is uncovered by the piston and scavenging the cylinder. One impeller thus delivers carburetted air and this may be richly carburetted air or merely normally carburetted according to the setting of the enriching valve. Preferably enriched air is used in the two cycle action. The other impeller thus delivers only pure air in two cycle action and scavenges the cylinders 2 periodically. In such two cycle action the control valve permits oil under pressure to enter the guide cylinders of both valves of two cylinders simultaneously and opens all these valves (being all the valves to cylinders 2 as shown) and thereby the valves being so opened at or near the time when the exhaust ports in the sides of the cylinders 2 are uncovered by the pistons, the carburetted air will enter (immediately after the scavenging action) and will drive a portion of the air or remaining gases in the cylinders out through the exhaust ports in the sides of the cylinders. This may be the setting or arrangement but preferably the engine is so constructed that for this two cycle action, the control valve will cause opening of the poppet valves and entry of carburetted air from the chamber 64 at a period immediately after the closing of the exhaust ports in the sides of the cylinders by the pistons as ascending, and thereby the pressure of the charge as created by the impeller will cause a filling of the cylinder 2 or cylinders 2 with an extra volume of carburetted air and air somewhat above the atmospheric pressure, say about ten pounds or so, and thereby there will be supercharging as a two cycle engine. Under such construction and operation as a supercharging two cycle engine, the scavenging air charge will cause scavenging with fresh air when the side ports are opened and when these side ports are closed the carburetted air charge (preferably enriched) will enter at about ten pounds pressure or so. Under this supercharging two cycle action the enriching valve is opened. Under two cycle action the two cylinders as shown fire simultaneously and each down stroke is a working stroke. The

engine would preferably have several or a plurality of such sets of two cylinders as those shown, and the arrangement of cylinders or combination may be varied as desired to secure the most efficient balanced action of the pistons.

As stated the operation may be varied from two cycle to four cycle or vice versa, according to the desire of the operator and the necessities of the load, but for starting the engine is preferably set for four cycle operation as the engine may be caused thereby to pick up speed easier. The impellers should preferably be so built and the speed of the electric motor such that the impellers will have sufficient speed to cause effective air charging or charging at speeds of the engine which will correspond to actual operating engine speeds at low driving speeds of an automobile. It is to be noted here that instead of the centrifugal impellers any form of blower as the Roots type may be used with the electric motors and in some constructions the impellers may be driven from the crank shaft through reduction gearing. With the use of the electric motor driving the impellers however as shown the engine will operate as readily two cycle at low speeds as at higher speeds and in fact probably better. As noted the impellers provide supercharging at two cycles. They also provide supercharging in four cycle operation and they also provide preheating by precombustion in the combustion chamber 56 and they also provide charging of the cylinders with fresh carburetted charge when the engine is at a standstill, in order that the engine may be readily started by the passing of a spark at the spark plugs.

The manner of operating the poppet valves by the control valve shown may be used or not as desired. While I have shown special devices and combinations of devices in the illustration of my invention I contemplate that other detailed devices and combinations may be used in the realization of my invention without departing from the spirit and contemplation of my invention.

What I claim is:

1. In an engine, a plurality of valves operating means therefor means delivering a liquid under pressure and a rotatable liquid distributor permitting delivery of the liquid under pressure and permitting release of the liquid from individual valve operating means periodically in accordance with the engine cycle and means whereby the distributor may be caused to open all the valves simultaneously and whereby carburetted charge may be caused to flow through the valves to the engine cylinders.

2. A valve actuating means comprising pistons individually associated with each valve of an engine, a cylinder related to each piston, a valve casing extended by the cyl-

inders having conduits severally delivering to each cylinder, a distributing valve rotatable in the valve casing and rotatable in cyclic relation with the engine, means whereby liquid under pressure is released by the distributing valve to each cylinder for cyclic actuation of the valves related to the pistons and whereby the cylinders are permitted to discharge during intervals intervening the respective opening periods, and means whereby the relation of the rotation of the distributing valve may be altered for alteration of the cyclic actuation of the valves so that under one condition of operation the engine may function as a four cycle engine and so that under another condition of operation the engine may function as a two cycle engine.

3. A valve actuating means comprising pistons individually associated with each valve of an engine, a cylinder related to each piston, a valve casing extended by the cylinders having conduits severally delivering to each cylinder, a distributing valve rotatable in the valve casing and rotatable in cyclic relation with the engine, means whereby liquid under pressure is released by the distributing valve to each cylinder for cyclic actuation of the valves related to the pistons and whereby the cylinders are permitted to discharge during intervals intervening the respective opening periods, and means whereby the relation of the rotation of the distributing valve may be altered for alteration of the cyclic actuation of the valves so that under one condition the distributing valve is in position to function for the regular cyclic operation of the engine and so that under another condition the distributing valve is positioned for opening of all inlet valves of the engine simultaneously for charging for starting and a blower charging means capable of delivering charging carburetted air during such condition.

4. An engine having a plurality of cylinders, valves related to the individual cylinders, pistons directly connected with the valves and reciprocable in related valve cylinders, a rotatable distributing valve rotatably mounted upon an axis passing adjacent to each valve cylinder and capable of governing the distribution of liquid under pressure to the individual valve cylinders in cyclic relation for actuation of the valves and permitting discharge from the valve cylinders during intervals intervening the respective periods wherein the valves open ports to their related cylinders, means whereby the relation of the rotation of the distributing valve may be altered for alteration of the cyclic actuation of the valves so that under one condition the engine may function as a four cycle engine and so that under another condition the engine may function as a two cycle engine, and means delivering liquid under pressure for such distribution.

5. An internal combustion engine having cylinders and cooperating pistons, ports communicating between the cylinders and an inlet manifold and ports communicating between the cylinders and an exhaust manifold, valve means governing the communication between the cylinders and manifolds, an air carburetting means connecting with the inlet manifold, means whereby the exhaust manifold may under four cycle actuation be connected with atmosphere and disconnected from the air carburetting means and whereby the exhaust manifold may under two cycle actuation be connected with the air carburetting means and disconnected from the atmosphere, means whereby the actuation of valve means may be altered for four cycle actuation and for two cycle actuation in relation to the engine pistons, and a blower means adapted to be actuated to blow carburetted air from the carburetting means to the manifolds under two cycle operation, and ports in the side wall of the cylinders adapted to release gases to the atmosphere when uncovered by the piston under two cycle actuation of the engine.

6. An internal combustion engine having cylinders and cooperating pistons, ports communicating between the cylinders and an inlet manifold and ports communicating between the cylinders and an exhaust manifold, valves means governing the communication between the cylinders and manifolds, means whereby the exhaust manifold may under four cycle actuation be connected with atmosphere and disconnected from the air carburetting means and whereby the exhaust manifold may under two cycle actuation be connected with the air carburetting means and disconnected from the atmosphere, means whereby the actuation of the valve means may be altered for four cycle actuation and for two cycle actuation, an electric motor adapted to drive an air blower and a blower blowing the carburetted air to the manifolds under two cycle actuation, and means whereby the air blower blows air to air inlet ports in the cylinder side walls for scavenging the cylinders through exhaust ports in the cylinder side walls under two cycle actuation when the side ports are uncovered by the related pistons.

7. An internal combustion engine having cylinders and cooperating pistons, ports communicating between the cylinders and an inlet manifold and ports communicating between the cylinders and an exhaust manifold, valve means governing the communication between the cylinders and manifolds, an air blowing means, means whereby the exhaust manifold may under four cycle actuation be connected with atmosphere and disconnected from the air blowing means and whereby the exhaust manifold may under two cycle actuation be connected with the air blowing

means and disconnected from the atmosphere, means whereby the actuation of the valve means may be altered for four cycle actuation and for two cycle actuation in relation to the engine pistons, means actuating the blower means, and ports in the side walls of the cylinders adapted to release gases to the atmosphere when uncovered by the piston under two cycle actuation of the engine, and means for the introduction of fuel cyclically to the engine cylinders.

In witness whereof, I have hereunto set my hand this 8th day of July, 1926.
